UNITED STATES PATENT OFFICE.

MICHAEL A. FLYNN, OF AKRON, OHIO.

TUBE VULCANIZER.

Application filed December 11, 1925. Serial No. 74,71

This invention relates to vulcanizers for inner tubes of pneumatic tires, being designed and intended to improve upon prior devices for this purpose, and particularly, intended and adapted for the vulcanization of inner tubes while in circular condition and while internally expanded by any suitable fluid pressure, such as air, gas or steam.

The invention is shown and described for use with chambered or steam jacketed molds and comprises a two-part shell or holder, preferably made from light metal such as aluminum, in which the tube is placed prior to vulcanization, the tube being subjected to slight inflation so as to cause it to fill out the shell, and the tube and shell being placed within the chambered mold which is properly shaped to receive the assembly thus obtained. By the use of the device a mold may be used economically and efficiently.

The advantages to be gained will be apparent to those skilled in the art, it being evident with a number of the shells or holders it is possible to properly position a tube within the shell while the latter is at room temperature, thereby avoiding the necessity of placing a tube within a hot mold, which is always objectionable from the standpoint of the workman and is also apt to burn or scorch the tube prematurely. By the use of the apparatus shown and described, these disadvantages are obviated and greater production is obtainable.

Additional objects are the provision of a shell which is strong and easily handled and which will avoid the formation of objectionable rinds or flashes at the lines of separation of the shell sections, the shell being so designed that the rinds referred to will occur at such points that injury of the tube or tire casing will be avoided.

Other objects and advantages will be obtained as evident to those skilled in the art to which this invention appertains and as will be pointed out in the claims, it being understood that changes and modifications may be made within the scope of the invention, which is not necessarily limited to exact conformity with the details set forth herein.

In the drawings:

Figure 1 is a view partly in elevation and partly in section, showing a complete mold unit with a tube therein;

Figure 2 is a cross-section on the line 2—2 of Figure 1; and

Figure 3 is a detail of the construction at the valve stem opening.

The main mold comprises two sections 1 and 2 which are divided along a plane through the center of the tube so that the mold can be opened for the removal and insertion of tubes and shells therein. The mold sections are shown as chambered for the circulation of steam, although other means may be used for heating the mold to proper vulcanizing temperature. Any suitable mechanism (not shown) may be utilized for holding the mold sections together.

The removable shell is shown as a whole at 3, being preferably made of any suitable material, aluminum being preferred for this purpose on account of its light weight and the ease with which it may be handled. The shell is shown as composed of two parts 4 and 5, the complete shell, when fitted together, enclosing a circular cavity to receive the tube. Being substantially in the form of a hexagon, four complete sides and a portion of the fifth are contained in the larger section 4, the remainder of the hexagon being formed by the section 5. Three sides of the shell 3 are received within correspondingly shaped recesses in each mold section.

In this connection it will be observed that the shell sections part along lines which are placed on one side of the tube and not directly along its inner and outer peripheries. The location of the lines of parting at the points indicated avoids the rinds at the tread and adjacent the rim. Heretofore the location of such rinds in tubes cured in the usual molds have been the cause of premature failure of the tire casing and tube.

At the point where the valve stem passes through the shell section 4, the latter is recessed, as shown at 10, so that the passage of the valve stem into position is not interfered with. The recess is arranged to be closed by a small piece of metal 11, which is pinned or otherwise secured upon the mold section 2 in position to fit within the recess when the mold is closed. The mold section 1 is cut away, as at 12, to permit the molding of tubes with bent valve stems, as shown in full lines in Figure 2, a straight valve stem being illustrated in dotted lines. A circular recess 14 is formed in the face

of the shell section 4 and the filler piece 11 to receive the circular washer 15 which is used to obtain the requisite compression of the tube about the base of the valve stem.

- 5 In the operation of the device a number of shells are provided for each mold and the tubes are placed with the shell section 4, while the latter is upon a table or conveyor, the shell resting for this purpose on 10 the surface x . The tube is now partially inflated and accurately seated within the section 4, the cover section 5 is placed over the tube, and the assembly is ready to be placed in a mold. When the mold is opened 15 and the vulcanized tube with its shell removed, a shell with an unvulcanized tube is dropped in its place and the mold closed, the heat of the mold not being dissipated while the tube is being placed in position. 20 The mold is now closed and air or other fluid under pressure is admitted to the interior of the tube through the valve stem and the tube will be vulcanized, as is understood by those skilled in the art. The form of shell may 25 be varied, but the substantial hexagonal section is preferred, as it affords a very strong construction and seats readily within the mold cavity.

What is claimed is:

- 30 1. In an apparatus for the uses and purposes set forth, a sectional mold, and a removable shell for receiving an inner tube, said shell being formed in two sections parting along lines lying between the inner and outer peripheries of the shell, the complete shell being receivable in cavities formed in the mold sections. 35 2. In an apparatus of the character described, a sectional mold, and a removable shell for receiving an inner tube, said shell being hexagonal in shape and formed in

two sections, one of said sections having four sides and a portion of a fifth side of said hexagon contained therein, the other section of the shell completing the hexagon. 45

3. In an apparatus of the character described, a sectional mold, and a removable shell receivable within said mold, the shell being formed in two sections which part 50 along lines within the inner and outer circumference of the shell, one of said sections covering approximately two-thirds of the total cross-sectional circumference of the tube, the other section completing the shell, 55 the mold sections having cavities therein to receive the complete shell.

4. An apparatus for the vulcanization of inner tubes comprising a sectional chambered mold having a recess therein which 60 is hexagonal in cross-section and a removable shell adapted to fit within the recess and adapted to contain the inner tube.

5. An apparatus for the vulcanization of inner tubes comprising a sectional chambered mold having a recess therein which is hexagonal in cross-section and a removable two-part shell adapted to fit within the recess and adapted to contain the inner tube. 65

6. An apparatus for the vulcanization of inner tubes comprising a sectional mold having a recess therein which is hexagonal in cross-section and a removable shell adapted to fit within the recess and adapted to contain the inner tube. 70

7. An apparatus for the vulcanization of inner tubes comprising a sectional mold having a recess therein which is hexagonal in cross-section and a removable two-part shell adapted to fit within the recess and adapted to contain the inner tube. 75
